UNITED STATES PATENT OFFICE.

THOMAS CARROLL, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,131,771.

Specification of Letters Patent.

Patented Mar. 16, 1915.

Application filed August 13, 1906. Serial No. 330,454.

To all whom it may concern:

Be it known that I, THOMAS CARROLL, a citizen of the United States, residing at Dayton, in the county of Montgomery and State of Ohio, have invented certain new and useful Improvements in Cash-Registers, of which I declare the following to be a full, clear, and exact description.

This invention relates to cash registers and has for a main object to provide an improved mechanism of the class described which will include a registering device and printing devices.

A second object is to provide an improved construction for preventing an operation of the counter when desired, as for example in connection with certain kinds of special transactions.

An improved printing mechanism including multiple type is provided which is normally at an intermediate position and therefore is arranged to take only a minimum movement to bring any desired type to printing position.

Another object is to provide an improved and automatic reversing device for an ink ribbon.

It may be desired at times to use the machine without the printing attachment and I provide means brought into operation automatically by the removal of the record holding means for preventing the operation of the printing mechanism.

The provision of the removable record holding means also has the function of providing for a segregated analysis of transactions. By the provision of the detachable means each clerk may be provided with an individual record strip holding means, and upon operating the machine he may insert his particular record holding means in the machine and receive upon the same a printed record of the transaction handled by him. In this way each clerk would have a printed record made by the machine of his individual sales. The machine may also be used to provide a separate record strip holding means for different cashiers when on duty, and as long as a cashier is on duty his record holding means may be permitted to remain attached to the machine, but on leaving the post the cashier would then detach his record holding means and the new cashier going on duty would substitute for the same his own

record holding means. In this manner the proprietor of an establishment employing a machine of this type will be enabled to ascertain just how much of the day's business was handled by the different clerks or cashiers in his employ.

With these and incidental objects in view, the invention consists in certain novel features of construction and combination of parts, the essential elements of which are set forth in appended claims and a preferred form of embodiment of which is hereinafter specifically described with reference to the drawings which accompany and form part of this specification.

Of said drawings: Figure 1 is a transverse section of a machine of a well known type to which I have shown my invention as applied. Fig. 2 is a rear elevation of the same. Fig. 3 is an elevation of one end of the machine showing the printing mechanism. Fig. 4 is a transverse section near the left hand end of the machine showing the controlling devices for the printing mechanism. Fig. 5 is a section on another line showing the throw out mechanism for the counter and the special keys and connections controlling the same. Fig. 5^a is a detail of a key arrester for the special keys. Fig. 6 is a detail showing the special printer and operating devices therefor.

My invention is adapted to be used with many types of cash registers and I have shown it as adapted for and applied to a prior invention for which Letters Patent of the United States numbered 879,081 and 909,775,09 did issue on February 11th, 1908, and December 6th, 1910, respectively, as well as other applications showing substantive improvement on the same. The machine is of the so called key operated type. The keys are arranged to differentially operate the register segments which are mounted on a pivoted frame. A common key member such as a key coupler is provided, the operation of which serves to rock the segment carrying frame and thereby bring the registering segments into gear with the register wheel pinions. To provide a throw out device for the counter I have arranged the counter on a pivoted frame and have provided means for connecting this counter frame to the frame of the register segments so that when the register segments frame is rocked the

counter frame will be moved also and the segments will remain out of mesh with the counter wheels.

The rear ends of the keys are adapted to engage differentially graded cam slots in plates, there being one for each denomination or bank of keys. These plates are connected to segments carrying a plurality of separately movable type which are by the 10 motion of the key brought to printing position.

The cam slots have not only different inclinations but are inclined in different directions so that some keys will move the 15 plate in one direction and some keys in a reverse direction thereby rendering necessary only a maximum movement of the type carrier of five steps instead of a maximum of nine steps as is the case in most prior 20 machines.

The record holding devices are arranged to be removed easily from the machine and means are provided for preventing the striking of the type hammers when such removal 25 has taken place.

I provide a reciprocating device for operating the ink ribbon feeding mechanism carrying two oppositely directed pawls with means for bringing them alternately into 30 operation the said means being controlled by the ribbon itself.

Described in general terms the machine comprises a series of keys 10 here shown as levers pivoted on the main rod 11 and 35 having a vertical portion 12 at the rear end thereof, this vertical portion having differently graduated slots 13. The cut away portions 13 are adapted to abut and move a rod 14 carried by arms 15 and the 40 frame including the rod and arms serves to differentially move the registering segments 16. The usual tablet indicators 17 are provided having their stems resting on the extreme rear ends of the keys. Each of the 45 keys 10 has a slot 18 in which a rod 19 of a key coupler 20 is adapted to move and thereby couple together any depressed keys. Referring now to Fig. 5 it will be seen that I provide a cam 21 having a depression 50 which normally engages an anti-friction roller 22 carried by a pivoted rod 23, this mechanism being duplicated at the two ends of the machine. The arms 23 are pivoted on the main rod 11 and serve with the rod 24 55 to form a rigid frame. This rod 24 carries the registering segments and it will be evident that when any key is depressed the cams 21 will serve to raise the arms 23 and thereby move the rod 24 to carry the segment racks 16 into engagement with the pinions 25 of the counter wheels this engagement being caused before the cut away portions 13 of the keys reach the rod 14. When 60 the keys reach the lower end of the stroke 65 the projecting arm 26 of the key coupler abuts against a cam device carried by rod 24 so that the coupler is then shifted laterally a sufficient distance to carry the cams 21 from under the rollers 22. On the instant that the key starts to return the arms 23 70 are allowed to drop back to normal position thereby carrying the segments 16 out of gear with the pinions 25 and this occurs before the segments have started their reverse oscillation due to the return of the 75 keys. It will be seen that this provides a one way connection between the segments and the counter wheels.

So much of the machine as has been described is shown in the prior patents and I 80 will now pass to a description of my present improvements and will first describe the so called throw out mechanism for the counter.

The machine is designed to take care of 85 different classes of transactions and some of these such as "Charge sales" "Money paid out" and "Money received on account" should obviously not be included in the register but a printed record of the same 90 is desired. I therefore provide means controlled by special keys representing the desired transactions for preventing the operation of the counter and to this end means are provided for coupling the arms 23 to 95 a counter carrying frame so that they will move together. In Fig. 5 I have shown the counter frame indicated by numeral 31. This is pivoted loosely on the rod 11. Mounted on the counter frame 31 is a bell crank 100 lever 32 pivoted at 33 and having an anti-friction roller 34 at one end and notches 35 and 36 near the other end. The notch 35 is normally surrounding a pin 37 carried by the counter frame. The notch 36 is normally over a flange 37^a on the arm 23. Special keys 38 are provided for the desired special transactions and these keys are also journaled on rod 11. Their rearwardly extending portions 39 have cam projections 40 110 adapted when the keys are depressed to engage the anti-friction roller 34 and elevate the same thereby rocking the bell crank 32 around its pivot 33 and serving to engage the notch 36 with the flange 37^a and to disengage the pin on the counter frame from the notch 35. It will be seen that this connects the counter frame 31 to the arms 23 and therefore that when the arms 23 are rocked through the elevation of the key 120 coupler the frame will be rocked as well so that the segments 16 will not engage the counter wheel pinions 25 and thereby operation of the register is prevented. To compel a complete depression of the special keys I 125 provide means for locking the mechanism during the stroke of the keys. The special keys 38 are provided as stated with rearward projections 39 the extreme rear ends of which are normally under the flange 41 130

of a lever 42 the same being journaled on a pin 43. The forward end of the lever 42 has a hook 44 adapted to engage a projection 45 of the cam 21 which is moved with the key coupler. When any special key 38 is depressed the rearward extension 39 thereof engages the flange 41 rocking the same rearwardly and depressing the hook 44 in front of the projection 45. When the key 38 is completely depressed the extension 39 passes above the flange 41 and the same time this moves forwardly under the key 38 as a spring 47 connects the lever 42 to a pin on the main frame of the machine. A projection 49 is provided on the cam 21 and this projection serves when the keys are completely depressed to engage a projection 50 on the lever 42 and restore the same to normal position thereby releasing the special keys.

The special keys 38 do not support indicators as do the value keys as it is not desired to expose the indicators until the value indicators are also elevated while it will be remembered that the special keys are depressed before the value keys. I provide therefore levers 51 one for each of the special keys which are also journaled on the main rod 11 and which serve to support special indicators 52. These indicators are arranged to be slightly elevated through connections set from the special keys so as to couple them to the key coupler which then provides for the further elevation of the said indicators. An arm 53 is provided journaled on the pin 54 on the counter frame and normally pressed forward as shown by a spring. This arm 53 carries on the lower end thereof a pin 55 which is adapted to be engaged by differently graduated cams on projections 56 of the special keys so that when any one of the keys 38 is depressed the arm 53 will be rocked rearwardly. Such rearward rocking serves to bring a flange 57 on the said arm over the forward end of the desired one of the levers 51. When the value keys are thereafter depressed the counter frame is rocked as it is at this time coupled to the arms 23 and this rocking serves to slightly depress the arm 53 so that its flange 57 abuts and moves the desired lever 51 and elevates the rear end of the same enough to couple it to the key coupler. The further operation of the value key serves to elevate the special indicator as well as the desired value indicator.

To prevent a depression of more than one special key at an operation I provide a key arrester shown in Fig. 5^a. It will be seen in Fig. 5 that the special keys have depending projections 61 and these are adapted to engage the spool shaped part 62 carried loosely on a rod 63. The depressed portion of the spool is only wide enough to allow one special key projection 61 to be moved

therein. If the center key 38 is depressed no movement of the spool 62 takes place while if either of the two outside special keys are depressed the spool is moved in one direction or the other but no two special keys can be depressed at the same time.

The printing mechanism is best shown in Figs. 2, 3 and 4. I provide plates 71 one for each bank of value keys at the extreme rear of the machine. These plates 71 have cut therein slots one for each key of the bank and the slots have differently graduated inclined portions 72. In the normal position these slots are directly over the keys 10 and it will be clear that the depression of the forward end of any value key will raise the rearward end thereof causing it to pass up the corresponding slot 72 and thereby cause a lateral movement of the plate 71, these plates being supported by a pin and slot connection 73 to allow such lateral movement. Each plate is connected to a link 74 and these links 74 are connected to bell crank levers 75 journaled on a rod 76. Connected to the levers 75 are vertical arms 77 having segment racks 78 as integral parts thereof, the arms being bent as shown in Fig. 2. As shown in Fig. 3 the racks 78 mesh with segments 79 which carry on the front ends thereof separate type bars 80. These type bars are separately carried by pin and slot connections on the segments 79 each type bar having thereon two numerals. The movement of the type bars to cause an impression on the record material is accomplished through the agency of hammers 81 these hammers being mounted on a shaft 82 and having a slot 83 in which a pin 84 of a lever 85 is adapted to ride. The lever 85 is journaled on a pin 86 and has a projection 87 with a notch 88 in which a lever 89 shown in Fig. 3 but better shown in Fig. 4 normally rests. When the lever 89 is rocked to carry it away from the notch 88 the lever 85 may rotate under spring tension thereby causing the pins 84 to ride down in the slots 83 and thereby throwing the hammers 81 forward against a type 80. To tension the spring 91 which operates the lever 85 I provide a bell crank lever 92 journaled on a pin 93. This lever has cut therein a cam slot 94 in which is adapted to ride an anti-friction roller 95 carried by an arm 96 rigidly mounted on the shaft supporting the key coupler and which is indicated by numeral 98. When the coupler is raised it will be clear that the roller 95 will ride upwardly in the slot 94 and serve to rock the bell crank lever 92 around its pivot 93 thereby tensioning spring 91. As shown in Fig. 4 spring 91 passes through a hole in a flange 99 on the lever 85 and is provided with a screw 100 the head of which will not pass through the hole in the said flange. It will be seen that in the normal position of the

parts as shown in Fig. 4 the spring 91 is under no tension but when the lever 92 is rocked as before described the spring will be tensioned and will bring the head of the screw 100 against a flange 99, movement of the flange being prevented by the lever 89. The arm 96 is provided with a projection 101 adapted to engage as the coupler reaches the end of its upward stroke with a pin 102 on the lever 89. As this lever 89 is journaled on the pin 103 it will be seen that at the end of the key coupler stroke the lever will be raised away from the notch 88 of the arm 87 and the spring 91 will then throw the type hammers 81 quickly forward to take an impression. When the keys return to normal position the lever 92 is reversely rocked and the lever 85 then returns to the position shown in Fig. 4 thereby carrying back the type hammers 81 through an arm 104 carrying a rack 105 engaging a pinion 106 on shaft 82. This arm 104 is moved forward by the hammer stroke and is returned by key coupler rod 19.

13 I have before stated that each type carrier 80 has two different type thereon but this causes no confusion of impression as the platen roller is of so small a radius as to curve away from the type not set for operation.

14 The record holding mechanism is provided to be easily removed from the machine and in such case it is not desired that the printing hammers should strike the type.

15 The record mechanism includes a holding roller 111 and a winding and feeding roller 112 as well as the platen roller 113. These rollers are mounted on pins carried by a plate 114 best shown in Fig. 4. The said plate has a cut away portion 115 near the bottom thereof which is adapted to surround a rod 116. A head 117 on the rod 116 prevents lateral movement of the plate 114. It will be clear that the plate 114 may be considered as pivoted on the rod 116 and means are provided for retaining the top of the plate in its desired position. This means includes a latch 118 adapted to be laterally moved manually when desired in which case the plate 114 may be rocked around rod 116 through a projection 119 at the top of the plate. It will be seen that the plate and the rollers carried thereby are a separable structure which may be easily removed by simply throwing the latch 118. To prevent the printing hammers from striking when the record holding means is withdrawn from normal position I provide an arm 121 normally pressed by a spring 122 to a position in the path of the end 123 of lever 85. This arm 121 is however normally held against the tension of spring 122 and in the position shown in Fig. 4 by a link 126 the forward end of which is adapted to contact with the projection 119 on the plate 114. The link

126 is provided with a slot surrounding a pin 127 to allow it a rearward and forward motion. It will be seen that when latch 118 is tripped and plate 114 rocked forwardly the projection 119 thereof will be moved 70 away from link 126 and the spring 122 will then operate to bring arm 121 over the projection 123 of lever 85. If with the parts in this position an operation of the machine is made the elevation of the coupler will 75 still raise arm 96 thereby rocking lever 92 and tensioning spring 91 but the upward movement of lever 85 will evidently be prevented by arm 121 so that no movement of the type hammers can take place.

130 To provide for feeding the record strip I use a link 131 connected to the previously mentioned lever 92. This link 131 is connected by a pin 132 to a lever 133 carrying a pawl 134 which is spring pressed to engage 85 the teeth of the ratchet 135 on the winding roller 112. The lever 133 and pawl 134 are carried by the frame of the machine but ratchet 135 is carried by plate 114 and will of course be removed when the said plate is 90 withdrawn. A retaining pawl 136 is provided to prevent backward movement of ratchet 135 and this is carried by a pin on plate 114. It will be seen from this mechanism that when the coupler is elevated arm 95 92 will be rocked thereby rocking lever 92 and drawing arm 131 rearwardly. This rearward motion will cause the actuating pawl 134 to move backward over the teeth of ratchet 135 and on the reverse movement 100 of the mechanism the pawl will be brought forward and will cause an actuation of the ratchet thereby serving to feed the record strip.

135 The ink ribbon and its feeding mechanism 105 are shown in Fig. 4. Two rollers 141 and 142 are provided which serve alternately as feeding rollers for the ribbon 143. Each of the rollers is provided with a ratchet 144 or, 145 having oppositely arranged teeth. 110 Journaled on the pin 146 is a vertical plate 147 having slots 148 in which pins 149 mounted on the main frame are adapted to move. It will be seen that this plate 147 can have no movement except a slight oscillation around its pivot 146, the extent of oscillation depending on the length of the slots 148. Two notches 151 and 152 are provided on the upper end of the plate 147 and an arm 153 is arranged to be drawn by a 120 spring 154 connecting the arm to the main frame into one or the other of the said notches thereby serving to hold the plate 147 in either of its two extreme positions. This plate 147 has mounted thereon two pins 161 125 and 162 adapted to ride in slots 163 and 164 of a pawl carrying plate 165. Mounted on pins at the extreme upper and lower ends of the plate 165 are operating pawls 166 and 167, the pawl 166 being adapted to engage 130

ratchet 145 for feeding roller 142 and the pawl 167 being adapted to engage ratchet 144 for feeding roller 141. Connected to the plate 165 by a pin 171 is a link 172 which is also connected by a pin 173 to the bell crank lever 92.

It will be remembered that lever 92 is oscillated at each operation of the machine by the raising and lowering of the coupler 10 and it will be clear that as plate 165 is connected by link 172 to the lever 92 that the plate 165 will be reciprocated at each operation of the machine and thereby cause a feed in one direction or the other of the ink ribbon. When the ribbon is completely unwound from one of the spools as is shown in Fig. 4 a succeeding operation of the machine will cause the pawl which is at the time operative, here shown as pawl 166 to 20 engage the tooth of ratchet 145 and endeavor to operate the same. The pawls 166 and 167 are provided with extensions 181 and 182 and these extensions are connected by a long spring 183. When the parts are 25 in the position of Fig. 4 and an operation of the machine is made the pawl 166 will as stated engage ratchet 145 but will be unable to rotate the same as the ribbon is completely unwound from the spool 141. The 30 pawl 166 will thereby rock around its pivot pin and throw the carrying plate 147 to its other position this being possible through the yielding of spring 154 which will cause the arm 153 to then engage notch 152 and 35 hold the plate 147 in its new position with pawl 167 adapted to engage the teeth of ratchet 144. It will be seen that this mechanism provides an automatic reversing device for the ink ribbon.

40 To print characters on the record strip indicating the special key if one has been depressed I provide mechanism shown in Fig. 6. The special keys 38 have edges 191 adapted to engage a rod 192 carried by arm 193 the arms being journaled on rod 63. The arms 193 are rigidly connected to a vertical bar 194 and this is connected through a link 195 to a bell crank 196 having at the forward end thereof a plurality of type carriers 197. It will be understood that the edges 191 of the special keys 38 are so shaped as to differentially rock the arms 193 and thereby bring the desired type 197 to the printing point. It will be seen that although there are only three special keys in the machine as shown I have provided four type 197. The type which is normally at printing position is adapted to cause an arbitrary character such as a dash to be 55 printed thereby indicating that a cash sale has been made. When however one of the special keys is depressed the corresponding type is brought to printing position and a letter indicating transaction is printed on 60 the strip.

It is desired to provide means for aligning the type carriers while they are being printed from and to this end I provide the segments 79 with a series of notches 201 as shown in Fig. 3. A plurality of pawls 202 70 carried rigidly by a shaft 203 serve to engage the notches 201 and to exactly place the type. These pawls are adapted to be rocked into and away from the notches by a plate 204 (see Fig. 5) also rigidly carried 75 by shaft 203. This plate 204 has a cam slot 205 cut therein and a pin 206 movable with the coupler rides in the said slot. It will be clear that as the said coupler is elevated pin 206 will finally reach the cam portion 80 of slot 205 and rock the plate 204 rearwardly. This will evidently serve to depress the pawls 202 into the proper notches 201 and lock the type until an impression has been taken therefrom. 85

To provide means for locking the printer operating plates 71 when no key in the corresponding bank is depressed I provide bent arms 211 these arms being shown in Figs. 1 and 2. These arms 211 are fastened to 90 the plates 71 and bent around and under the keys. The forward ends of the arms are bifurcated and in the bifurcations levers 212 are adapted to engage, thereby locking the plates 71 against lateral movement. The 95 levers 212 have at the forward ends thereof lateral rods 213 extending under the keys of the corresponding bank. It will be seen that while the bent arms 211 are normally locked against lateral movement by the 100 levers 212 that a depression of any key in the bank will depress the pin 213 thereby elevating the rear end of a lever 212 enough to allow lateral movement of the arm 211 and consequently to allow the printing devices to be set. 105

It is desired that the mechanism should be locked while the counter is being returned to zero and mechanism for accomplishing this result is shown in Fig. 5. The counter 110 shaft is indicated in this figure by the numeral 221 and it has mounted thereon a disk 222 cut away as indicated at 223. The lever 42 previously referred to has connected at its upper end a bar 224 which has a slot 115 225 surrounding the shaft 221 and serving to guide the arm. Pin 226 is mounted in the forward end of the arm 224 and normally rests in the cut away portion 223 of the disk 222. It will be clear that when 120 disk 222 is rotated by turning the shaft 221 to reset the counter that pin 226 will be forced forwardly thereby rocking the lever 42 and depressing the projection 44 in the path of projection 45 on cam 21. This evidently locks the mechanism as cam 21 is carried rigidly with the key coupler. It will be evident that such rocking of lever 42 will move rearwardly the flange 41 at 125 the bottom of said lever thereby serving to 130

release a special key if such key has been depressed. The operation of the machine will be clear from the foregoing description but it may be briefly described as follows. To register an amount the keys 10 corresponding to the amount are depressed and then allowed to resume their normal position. When the keys are depressed the coupler 20 rises with the rear ends of the 15 keys thereby rotating the cam 21 and raising arms 23 and rod 24 carrying the segments 16 which actuate the counter wheels into mesh with the said wheels. The further depression of the keys serves to raise 20 the cut away portion 13 thereof to engage the rod 14 and to thereby rock the segments 16 to add the desired amount on the counter. When the keys reach their lowest position the coupler is moved laterally and the cam 21 thereby carried from under the rollers 22. When the keys 10 start to return the arms 23 immediately drop allowing the segment 16 to be withdrawn from the counter wheels and the segments are thereafter 25 turned to normal position out of mesh with the said wheels.

The depression of any value key 10 depresses the rod 213 thereby elevating the rear end of the lever 212 corresponding to 30 the bank in which a key has been depressed. The raising of lever 212 releases the rocking arm 211 so that a plate 71 for the bank of keys may be moved laterally as the rear end of the key passes up the slot 72. This 35 lateral motion of the plate 71 serves to set the corresponding printing segments 79 through the link 74, lever 75 and bent arm 77. As the coupler moves upward the arm 96 carried therewith rocks lever 92 and 40 thereby tension spring 91. As the coupler reaches its uppermost position projection 101 rocks the lever 81 thereby releasing the lever 85 when the spring 91 immediately elevates the said lever and causes the pin 84 45 carried therewith to throw the printing hammer 81 against a type carrier to force said carrier to impressing position. The forward movement of lever 85 serves to move forward the arm 104 through the pinion 106 mounted on shaft 82. When the 50 keys return to normal position the rod 19 of the key coupler strikes the forward edge or arm 104 moving the same rearwardly thereby returning the printing hammers to 55 normal position in which they are locked by the lever 89.

When a special transaction is to be entered in the machine the operation is in large part the same as when the cash sale is registered. In this latter case however a special key is first depressed and the cam 39 carried thereby rocks lever 32 around its pivot 33 and thereby serves to connect the arms 23 with the counter frame 31. When the 65 arms 23 are rocked around their pivots 11

the counter frame will be also moved so that the segments 16 remain out of mesh with the register wheel pinions 25 and no amount is added on the counter. It will of course be remembered that this operation of rocking 70 the counter frame does not take place until the value keys are depressed. The depression of the special key serves to lock the machine until the key has reached its lowermost position through the movement of lever 42 which is cammed by the rear end of the special key. When the special key is depressed the depending projection 56 thereof rocks the arm 53 to bring a flange 57 over the desired indicator lever 51. When the 80 value key is depressed and the counter frame rocked flange 57 slightly raises the rear end of lever 51 to couple the same to the coupler so that when the value keys are thereafter operated the special indicator will be raised. 85 The depression of the special key serves to position a printing device through the mechanism shown in Fig. 6. At each oscillation of lever 92 the ink ribbon feed pawls are reciprocated to slightly feed the record 90 material.

The record holder may be removed by tripping latch 118 when the arm 121 immediately springs forward and serves to prevent the operation of the printing hammers. The type segments 79 are locked 95 while the printing takes place by the pawls 202 controlled from camming arms 204.

It will be seen that the machine is normally adapted to both print and register the 100 amount indicated on the value keys but it will of course be understood that the printing devices or the registering device may be dispensed with. When a special transaction is to be entered the register is automatically prevented from operation. The 105 operation of the printing mechanism may be dispensed with by merely tripping the latch thereby permitting the record holding plate to move slightly forward.

While the form of mechanism here shown and described is admirably adapted to fulfil the objects primarily stated, it is to be understood that it is not intended to confine the invention to the one form of embodiment herein disclosed, for it is susceptible of 110 embodiment in various forms all coming within the scope of the claims which follow.

What is claimed is as follows.

1. In a cash register, the combination with 115 register wheels, of oscillating racks for operating same, means for moving the racks to bring said wheels and racks together for operating the register wheels, and means for moving said register wheels when no operation of the register wheels is desired.

2. In a cash register, the combination with 120 a register, of operating racks for same, means for moving said racks to bring them into gear with the register, and means for 125

130

- moving said register with the racks when no operation of said register is desired. 65
3. In a cash register, the combination with a register and a pivoted frame supporting same, of racks for operating same, means for bringing said racks and register together, and means for rocking the register frame to prevent an operation of said register. 70
- 10 4. In a cash register, the combination with a register and devices for operating same, of means for moving said register away from said devices, to prevent an operation of the register. 75
- 15 5. In a cash register, the combination with a register and a frame for carrying the same, of racks for operating said register and a frame for carrying said racks, means for rocking said latter frame to cause an engagement of said register and racks when said register is to be operated, and means for rocking both of said frames when said register is not to be operated. 80
- 20 6. In a cash register, the combination with a register and a frame carrying same, of a plurality of operating racks, and a frame supporting said racks, means for moving one of said frames to engage said register and racks, and means for coupling said frames together when no operation of the register is desired. 85
- 25 7. In a cash register, the combination with a register and a pivoted frame carrying same, a series of operating racks for same and a frame carrying said racks, means for rocking the rack carrying frame to bring said racks into mesh with the register, and means for coupling the rack frame to the register frame when no operation of the register is desired. 90
- 30 8. In a cash register, the combination with a register and a frame carrying same, a plurality of racks for operating said register and a frame carrying said racks, and special keys for coupling said frames. 95
- 35 9. In a cash register, the combination with a register and a frame supporting same, of operating devices for said register, a frame carrying said devices, means for moving one of the frames, and special keys for coupling the two frames. 100
- 40 10. In a cash register, the combination with register wheels, of oscillating racks for same, means for bringing said wheels and racks together to operate the wheels and special keys for connecting the wheels to the racks when no operation of the wheels is desired. 105
- 45 11. In a cash register, the combination with a register and means for supporting it, of operating devices for the register and means for supporting said devices, means for bringing the operating devices and register together and special manipulative devices for connecting the supporting means for the register and operating devices when no registration is desired. 110
- 50 12. In a cash register, the combination with a plurality of levers and indicators supported thereby, of an actuating device for said levers, means for adjusting said actuating device to coöperate with any lever and a key coupler for operating said levers. 115
- 55 13. In a cash register, the combination with value keys and a key coupler operated thereby, of a plurality of levers and indicators supported thereby, special keys, a device adjusted thereby to coöperate with any desired lever, and means for moving said device to connect the desired lever to the key coupler. 120
- 60 14. In a cash register, the combination with value keys and a key coupler operated thereby, of special keys, and levers one for each key, a device adjusted differentially by the special keys to operate any desired lever, indicators operated by said levers, and means for operating said device to engage the levers to the key coupler. 125
- 65 15. In a cash register, the combination with a plurality of indicators and levers for operating same, of special keys, a device adjustable by said keys to position to operate any desired lever, and a main operating device for operating the lever selected. 130
- 70 16. In a cash register, the combination with a plurality of indicators and devices for supporting same, of a main operating device for said levers, a plurality of keys, a device adjusted differentially thereby to position to engage the desired lever, and means to operate the said device to connect the selected lever to the main operating device. 135
- 75 17. In a cash register, the combination with value keys and a common member operated thereby, of special keys arranged to be preliminarily depressed, a device differentially set by the special keys, a plurality of levers adapted to be connected by said device to the common member, and means for locking the common member during the stroke of the special keys. 140
- 80 18. In a cash register, the combination with printing mechanism including impression means for causing an impression to be made, record holding devices structurally separate from said printing mechanism, and supporting means for supporting said devices singly adjacent said printing mechanism whereby to enable a segregate analysis of transactions. 145
- 85 19. In a cash register, the combination with printing mechanism including impression means for causing an impression to be made, record holding devices structurally separate from said printing mechanism, supporting means for supporting said devices singly adjacent said printing mechanism whereby to enable a segregate analysis of transactions, and means for disabling said 150

impression means in the absence of a record device from printing position.

20. In a cash register, the combination with printing elements, of hammers for causing an impression to be made from the same, a platen and supporting mechanism therefor and removable from the cash register, a latch for normally locking said mechanism in operative position, and means for preventing a hammer stroke when the supporting mechanism is out of operative position.

21. In a cash register, the combination with printing elements, of removable means for holding a record, hammers for causing an impression to be taken from the printing elements, means controlled by the record holding means for preventing the hammer stroke, and a latch for normally holding said removable record means in operative position.

22. In a cash register, the combination with printing mechanism including means for taking impressions therefrom, means for preventing the operation of the impression taking means, a record holding means removable from the cash register and adapted to disable said preventing means when in operative position, and a latch for normally holding said record holding means in operative position.

23. In a cash register, the combination with type carriers, of hammers for forcing

the same to print, a record holding means removable from the cash register, means under control of said removable means for preventing operation of said hammers, and a latch for latching said record holding means in operative position.

24. In a cash register, the combination with type carriers, of means for taking impressions therefrom, record holding means removable from the cash register, a latching device for normally holding said removable means in operative position, and means under control of said record holding means for preventing an operation of the impression taking means when said holding means is out of operative position.

25. In a cash register, the combination with type carriers, and hammers for striking the same, of record holding rollers, a plate carrying said rollers and removable from the cash register, means for supporting said plate, a latching device for normally holding said plate in operative position, and means under control of said plate for preventing an operation of the hammers when the plate is out of operative position.

In testimony whereof I affix my signature in the presence of two witnesses.

THOMAS CARROLL.
